John A. Bonnhardt
ATTORNEY.

UNITED STATES PATENT OFFICE.

ANTON NOSAN, OF CLEVELAND, OHIO.

DRIVING MEANS FOR AEROPLANE PROPELLERS.

Application filed August 18, 1926. Serial No. 129,981.

This invention relates to improved means for driving a pair of propellers, such as aeroplane propellers, from a single engine, and it includes means for reversing or adjusting the pitch or angle of the propeller blades, such as disclosed in my pending application filed Feb'y 8, 1926, Serial No. 86,883, the present invention, however, providing means for simultaneously adjusting the blades of both propellers, from a single operating lever. The embodiment shown herein effects the simultaneous operation of both propellers by means of gears between the engine shaft and the propeller shafts, the propellers being located side by side at the end of the aeroplane, but staggered transversely and with the plates set at right angles to each other so that each plate acts on a different portion of the air, altho the propeller shafts may be set so close to each other that the pairs of blades overlap.

The invention is illustrated in the accompanying drawings, in which Fig. 1 is a fragmentary view of the aeroplane with the improved propeller arrangement. Fig. 2 is a front view thereof.

The engine is indicated at 5 mounted in the present showing in nose 6 of the fuselage 7 and the engine crank shaft 10 has near its end a driving gear 9 which meshes at opposite sides with driven gears 11 on a pair of propeller hubs 12 having blades 13 mounted thereon.

These blades may be pivoted to the hub 35 and turned or reversed by means described in my said pending application, said means including spring collars 14 having grooves 15 engaged by fingers 16 of sleeve 17 slidably mounted on the propeller supporting arms 40 18 extending along the opposite sides of the nose 6 of the fuselage. The hubs 12 are journaled in a cross bracket 19 mounted on the front of the fuselage, which holds the propellers in position. The sleeves 17 are 45 connected by rods 20 to racks 21 which mesh with pinions 22 carried by transverse shaft 23 which may be turned by a lever 24 in the control compartment, these rods and shaft being carried in suitable supports on 50 the fuselage. The pitch or angle of both propellers may be adjusted by the operation

of lever 24 which shifts the rods 20 backwardly or forwardly and by the means described turns the propeller blades to different angles. The details of the devices in hubs 12 55 may be such as those shown in my said pending application or any other suitable devices for adjusting the pitch of the blades.

It will be noted that one propeller is set sufficiently in advance of the other to enable 60 the blades of the different propellers to pass each other, as particularly shown in Fig. 1. Also, the blades are set at right angle so that they act on different portions of air or other medium. This staggered arrangement permits the use of two propellers in a close compass and with the full effect of each propeller. It is obvious that by means of gears 9 and 11 both propellers are driven from the single crank shaft and a very effective 65 operation is produced. Altho the propellers are illustrated at the front of the machine, obviously they may be changed to opposite ends. The supports and gearing for the two propellers are simple and easily 70 accessible, and the arrangement permits the convenient mounting of blade shifting mechanism on a stationary support at each side of the fuselage, and the adjustment is simultaneous and equal for both propellers, 75 so that no distortion or change of direction follows from such adjustment.

Various changes may be made within the scope of the invention as defined in the following claim.

I claim:

The combination with an aeroplane fuselage, of a cross bracket mounted on one end thereof, twin propellers with adjustable blades, having hubs mounted in bearings at 90 opposite ends of said bracket on opposite sides of the center line of the fuselage, a single engine mounted in the fuselage, and having a shaft projecting therefrom between said hubs, gearing between the shaft and the 95 propeller hubs, at the outer side of said bracket, and control rods for adjusting the blades, extending into the hubs at the inner side of said bracket.

In testimony whereof, I do affix my signature.

ANTON NOSAN.
